DESIGN FOR A FOLDING MACHINE OR SIMILAR ARTICLE

William Ward Davidson, Evanston, and Harry S. Scholl, Glen Ellyn, Ill.; said Scholl assignor to Davidson Manufacturing Corporation, Chicago, Ill., a corporation of Illinois

Application April 3, 1941, Serial No. 100,119

Term of patent 14 years

To all whom it may concern:

Be it known that we, William Ward Davidson and Harry S. Scholl, citizens of the United States of America, and residents of Evanston, county of Cook, and State of Illinois, and Glen Ellyn, county of Du Page, and State of Illinois, respectively, have invented a new, original, and ornamental Design for a Folding Machine or Similar Article, of which the following is a specification, reference being had to the accompanying drawings, forming a part thereof, wherein

Fig. 1 is a perspective view showing one side of a folding machine embodying our design; and
Fig. 2 is a perspective view showing the other side of said folding machine.

What we claim is:

The ornamental design for a folding machine or similar article, substantially as shown.
